GAME FOR PLAYING FOOTBALL

Filed March 26, 1925

UNITED STATES PATENT OFFICE.

JAMES E. RYAN, OF CRESTON, IOWA.

GAME FOR PLAYING FOOTBALL.

Application filed March 26, 1925. Serial No. 18,485.

To all whom it may concern:

Be it known that I, JAMES E. RYAN, a citizen of the United States, residing at Creston, in the county of Union and State of Iowa, have invented certain new and useful Improvements in a Game for Playing Football, of which the following is a specification.

This invention relates to an improved toy game for enabling participants to literally play football at home, the same having reference to a toy, by means of which the actual game of football as played upon a field is simulated.

The purpose of the game is to enable persons, particularly those interested in actual football games to thoroughly acquaint themselves with the various plays of the game and to permit them to exercise and display skill and knowledge of the game, the device being both educational and serving to provoke considerable amusement to the participants.

The invention has more particular reference to a rotatable indicator which is effectively concealed in a housing, this indicator bearing various indicia and instructions for registry with a restricted sight opening, the roller or indicator being set into motion by a mechanical device, which renders the point of stoppage of the roller indefinite, so that varied instructions are given for a selected play, either of advantage or disadvantage, as the case may be to the respective participants.

In addition to this mechanical device, the invention embodies a novel tally board, enabling an accurate score of the points and clear representation of the various plays to be recorded.

The various features and advantages of the invention will become apparent from the following description and drawings.

In the accompanying drawing, forming a part of this application, and in which like numerals are employed to designate like parts throughout the same:

Figure 1 is a front elevation of the mechanical device, which is operated by the various individuals or participants in ascertaining the instructions to be followed upon selected plays.

Figure 2 is an end elevation, enlarged, of the device seen in Figure 1, showing the con-

struction of the mechanical operating means more clearly.

Figure 3 is a top plan view of the tally board.

Figure 4 is a perspective view of a movable indicator.

Figure 5 is a view showing a linesman's marker.

Figure 6 is a view of the football used.

Figure 7 is a detail view, of a down recorder.

Referring to the drawings and confining attention more particularly to Figures 1 and 2, it will be seen that the reference character 1 designates a box, the rear wall of which is of considerable elevation as indicated at 2. At the right hand end and on the front, the box is provided with a standard 3 and a top piece 4 is connected with the standard and with the top of the back wall 2. Mounted for rotation in the box is a cylinder, constituting an indicator 5. At one end, and on one of its journals, the indicator is equipped with a gear 6. The lower laterally directed end of a spring returned plunger 8 is adapted to engage with the teeth of the gear for acting both as a means for imparting rotation to the cylinder, and as a brake for stopping rotation. It will be noted that the plunger is formed on its top with an appropriate knob 9, to facilitate depression. Also, as shown in Figure 2, a guide bracket 10 is employed to insure proper alignment of the plunger with the gear. An appropriate shield 11 extends over the box and cylinder, and this shield is provided on its front side with an elongated slot 12 forming a restricted sight opening. Rectangular areas 13 are marked off and are disposed in alignment with the top of the slot. In each area is printed or otherwise displayed an expression 14 defining one of the major plays made in an actual game of football. For instance, such expressions as "Kick-off" "Forward pass" etc. Cooperating with these areas 13 are designations or instructions carried by the surface of the cylinder 6. In carrying out this end, the cylinder is divided into circumferential bands 16, and these bands are of a corresponding width to the length of the aforesaid areas 13, each band being divided into circumferential blocks, in which various designations 16 are

displayed. For instance, in that band aligned with the area 13 containing the play "Off tackle" we find the expression "No game" displayed. In this same band 5 are various other expressions, such as "Two yard loss" "Five yard gain" etc., and these expressions will be brought into alignment with the last named area 13, to cooperate therewith in giving instructions for that 10 particular play.

On accessory used in connection with the mechanical device just described is the tally board, 17, shown in Figure 3. This tally board is provided at the left hand end with 15 an area 18, in which the various downs are displayed. In this area will be found four sockets 19 beside which appear the words "First", "Second", etc. The purpose of these will be later described. The surface of the 20 board is marked off into main lines 20, indicating five yard distances, upon the playing field. These five yard lines are accompanied by numerals, such as 35, 40, and so on. Between the five yard distances are 25 auxiliary lines 22, indicating one yard gains and losses. The board as just marked depicts an actual foot ball field, the zero marks at the opposite ends indicating the goals. It will also be observed that there are two 30 rows of openings 23 and 24 respectively, the openings of each row being in fixed alignment. The purpose of these will be referred to later.

In Figure 5 I show a linesman's marker, 35 comprising a flag 25 having a pointer and provided at its opposite end with stakes 26. These stakes are adapted to be placed in the openings 23, forming the uppermost row on the playing field. In Figure 6 I 40 show a ring 27 provided with a stem 28, and this is to represent the football. In Figure 7, I show a miniature frame 29, having a stem 30, adapted to be selectively seated in one of the aforesaid sockets 19, to 45 indicate the particular down at any stage of play.

Assuming that it is desired to engage in a foot ball battle, and that two participants are to play, it will be seen that the indicator 50 31 (Figure 4) having the hooked end 32 is hooked over the edge of the sight opening 12 and is moved along as a slide to indicate to the opponents what play is to be made. For instance, when the game is 55 started, one participant who is supposed to kick off, places the indicator 31 opposite the area 13 bearing the expression "Kick-off". He now depresses the plunger 8 and in so doing sets the cylinder 5 into rotation. 60 The momentum imparted to the cylinder rotates it rapidly, and as soon as the plunger is released, the spring returns to its raised position, and the laterally directed lower end thereof constitutes a brace engaging the

gear 6 and stopping the cylinder instantly. 65 In so doing, any one of the numerous instructions displayed in the band 15, opposite the kick off area may come to view. For example, as shown, the expression "Returned to 20 yard line" is displayed. This means 70 that the opponent who is the recipient of the ball, places the ball on his twenty yard line and proceeds to rush the same up the field. At this point of play the participants stop to place the ball 27 in the opening 24 75 on the twenty-yard line on the right hand side of the center of the field. This indicates the position of the ball. The marker 25 is now brought into play and one stake is anchored in the hole 23 opposite the last 80 named hole 24, while the other stake is anchored on the thirty yard line, thus serving to indicate the portion of ground that must be gained within the allotted fourth down. With the ball in the opponent's 85 hand, the opponent must indicate what play he contemplates making upon the first down. To do this, he moves the slide or indicator 31 opposite the area 13 selected. In this instance, he must exercise his own skill in 90 selecting a play which would be carried out under corresponding conditions, or on an actual playing field. Assume that he desired to proceed on the first down with a "line buck". Obviously, he moves the slide, 95 as shown in Figure 1, opposite this indication. He now spins the cylinder, and when it stops, it displays the expression "Two yard gain". Then he moves the ball 27 up 100 two yards. Of course, any one of a number of numerous indications could have come into sight at this time, for instance, it may have been a fumble, and the other side would take the ball, possibly at a one or two yard loss. The operator proceeds to 105 play until he loses the ball to the other side, and if, in the meantime, he scores any points, these are placed upon an appropriate score card, and added, when the game is over. It is of course, understood that the 110 member 29 is employed in the socket 19, to indicate the various downs, after each play is made.

In order that the reader may obtain a more definite idea of the rules of play, at 115 110 intention is directed to the following:

The procedure of play is in every respect governed by the official rules of foot ball, except that in this game, the place or drop kick is only permissible when on or inside 120 the 30 yard line.

The following extracts from the official rules are submitted.

"The length of the game shall be 60 minutes, divided into four periods of 15 125 minutes each, exclusive of time taken out, although it may be of shorter duration, by mutual agreement."

(5 minute periods are suggested.)

"The game shall be decided by the final score at the end of the four periods. The following shall be the value of plays in

scoring:

Touchdown ----- 6 points
Successful 'try' after touchdown-- 1 point
Goal from the field ----- 3 points
Safety by opponents ----- 2 points."

10 "A touchdown is made when the ball, lawfully in possession of a player, is declared dead by the referee, any part of it being on, above or behind the opponent's goal line."

15 "A try-for-point is the privilege granted the side which has made a touchdown to add one additional point to its score by successfully executing a single play from scrimmage."

20 "A goal from the field is made by kicking the ball from the field of play either by a drop kick or a place kick over the cross bar of the opponent's goal."

25 "A safety is made when the ball in possession of a player guarding his own goal is declared dead, any part of it being on, above or behind the goal line, provided the impetus which caused it to pass from outside the goal line to or behind the goal line."

30 was given by the side defending the goal."

35 "If in four consecutive downs a team, having constantly had the ball in its possession, shall not have advanced the ball 10 yards, it shall go to the opponents on the spot of the fifth down."

The present toy game is likened to the actual game, in that it is primarily a game of skill and stratagem, and luck enters only in a very minor degree. The game, as actually constructed, is compiled strictly from actual statistics gathered from evenly matched college games, the outcomes of which would have been altered had the system of plays been improperly directed.

That is true with the present game. In 45 this game, the players are themselves the field generals and must direct each play. Hence, the benefit derived from a device of this kind cannot be over-exaggerated.

It is thought that the description, taken 50 in connection with the drawings, will enable persons skilled in games of this kind to obtain a very clear understanding of the same, and for this reason a more lengthy description is deemed unnecessary.

55 While the preferred embodiment of the invention has been specifically described and shown, it is to be understood that minor changes coming within the field of invention may be resorted to, if desired.

60 I claim:

In a game of the class described, a housing comprising a box substantially covered by an arcuate shield having a sight opening formed therein, there being marked areas along one edge of the opening bearing words and phrases designating plays to be made, a rotary indicator mounted for rotation in said housing and embodying circumferential marked bands aligned with 70 the aforesaid areas and containing various results capable of being obtained from said plays, a gear carried by the rotary indicator, a vertically disposed plunger, a support on said box for said plunger, the lower 75 end of said plunger being directed laterally to provide a lug for cooperation with the teeth of said gear, a coil spring surrounding the plunger between the support and head on the upper end of the plunger, a 80 guide for said plunger, and a separate and independent element embodying a hook slidably mounted in said sight opening and adapted for cooperation with the aforesaid areas.

85 In testimony whereof I affix my signature.

JAMES E. RYAN.
